UNITED STATES PATENT OFFICE.

CLAUDE A. GUNDER, OF JEFFERSONVILLE, INDIANA, ASSIGNOR TO AMERICAN VENDING MACHINE CO., OF JEFFERSONVILLE, INDIANA.

VENDING-MACHINE.

No. 817,912.

Specification of Letters Patent.

Patented April 17, 1906.

Application filed June 16, 1905. Serial No. 265,599.

To all whom it may concern:

Be it known that I, CLAUDE A. GUNDER, a citizen of the United States, residing at Jeffersonville, in the county of Clark and State 5 of Indiana, have invented certain new and useful Improvements in Vending-Machines, of which the following is a specification.

Machines of the type actuated by coin are frequently operated by slugs, dummies, and 10 other articles simulating the prescribed coin. This invention deals with means to obviate this practice by diverting articles other than the predetermined coin away from the coin-actuated mechanism, thereby preventing de- 15 frauding of the machine.

It frequently happens that the machine becomes choked by slugs lodging therein, thereby putting it out of commission. This 20 invention obviates this difficulty, since it provides for clearing the machine of obstructing matter at each operation of the vending-slide.

The invention consists of a coin-race having a movable wall and an open bottom, the latter being of a width and length to insure 25 the dropping therethrough of a slug or like article a fraction smaller than the given coin, said coin-race inclining transversely, preferably away from the movable wall, to render more certain the rejection of the slug. A 30 magnet located at one side of the coin-race attracts iron slugs laterally, the side wall being cut away to provide a ready escape.

For a full description of the invention and the merits thereof and also to acquire a 35 knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment is shown in the accompanying drawings, in which—

Figure 1 is a front view of a vending-machine embodying the invention, the upper portion being broken away and the bottom portion being partly in section. Fig. 2 is a vertical transverse section on the line $\alpha-\alpha$ of Fig. 1. Fig. 3 is a longitudinal section of the fraud-preventive mechanism on a larger scale. Fig. 4 is a side view of the mechanism shown in Fig. 3. Fig. 5 is a perspective view of the fraud-preventive mechanism. Fig. 6

is a detail perspective view of the movable or pivoted side of the coin-raceway. Fig. 7 is a detail view showing the means for locking the vending-slide when the magazine is empty.

Corresponding and like parts are referred to in the following description and indicated in all the views of the drawings by the same reference characters.

The cabinet-work for inclosing the goods to be vended and the operating mechanisms may be of any design and construction according to the whim and caprice of the constructor.

The cabinet is indicated by the reference-numeral 1, and within the same is arranged the magazine 2 for containing the goods to be vended in the form of packages. The vending-slide 3 is operated by means of an arm 4, extended from a rock-shaft 5, which is operable from a point without the machine in any convenient manner. The goods when discharged from the magazine drop upon the oval plate 6, from which they are removed in the usual way. The coinway has a portion arranged at the rear of the cabinet, as shown at 8, and a portion 9 at one side in connection with the part 8. The coin 10 is received in a pocket or opening formed at one end of the vending-slide 3, and an edge portion projects into the path of the lower-most package of goods. Thereby upon movement of the vending-slide said package is pushed laterally from beneath the pile and caused to drop into the receptacle 6. These parts may be of any construction and are subordinate or adjunctive in nature to the present invention, which relates most especially to the fraud-preventive mechanism.

The coin-slot, through which the prescribed coin is introduced into the machine, is represented at 11, and the coin-race extends therefrom at a downward inclination and terminates at its inner lower end some distance from the receiving end of the coinway 8, whereby provision is had for rejection of a slug, dummy, or other article that may be employed for operating the machine. The coin-race comprises a bottom 12, a fixed side wall 13, and a movable side wall 14, which latter is preferably pivoted, and for this purpose has a lateral extension 15 at its upper end overlapping the bottom 12 and pivoted at one end, as shown at 16. The bottom 12 is open, as shown at 17, to provide a ready

escape for articles having a less diameter than the predetermined operating-coin. The movable side 14 is provided at its base with an inner ledge 18 of a width to engage with the rim of the operating-coin, but will not engage with a slug or like article having a diameter slightly less than that of the prescribed coin. A hook 19 at the upper end of the side 14 engages under the upper portion of the bottom 12 and holds the side 14 in close engagement with said bottom. A spring 20 exerts a lateral pressure against the movable side 14 to maintain it in a given position. The arm 21 is pendent from the movable side 14 and is adapted to be engaged by a trip 22, connected with or operated by means of the vending-slide 3. An extension 23 of the arm 21 constitutes a stop and engages with the bottom 12 or other portion of the mechanism so as to limit the inward movement of the side 14 under the influence of the spring 20. The coin-race inclines transversely, the inclination being from the movable side 14 downward toward the fixed side 13, whereby the article introduced through the coin-slot 11 maintains close engagement with the side 13 by gravitational action, with the result that the higher edge clears the supporting-ledge 18 should the article be of a less diameter than the operating-coin. The lower end portion of the side 13 is cut away so as to provide a lateral discharge for slugs or dummies of iron or other magnetizable material. An extension 24 is provided in contiguous relation to the space formed by cutting away the lower portion of the side 13 so as to receive the slug or dummy and form a support therefor during its lateral movement, whereby it is prevented from dropping through the opening 17 of the bottom 12. A magnet 25 is located at one side of the coin-race and exerts an influence upon iron slugs or dummies which are attracted and caused to discharge laterally from the race.

45 The vending mechanism embodying the invention is adapted to be actuated in the usual manner upon depositing a coin of determinate value in the slot 11. Upon introducing a slug having a diameter slightly less than that of the prescribed coin said slug will drop through the opening 17; but should it be a trifle larger than the prescribed coin it will stick in the coin-race, as frequently the case, and interfere with the subsequent operation of the machine. This objection is overcome in the present instance by the movable side 14, since upon operating the vending-slide the trip 22 being actuated presses the side 14 upward or outward, thereby releasing the slug and permitting it to drop through the opening 17 and clearing the machine for proper operation upon introducing a coin of given value in the slot 11. An iron slug or dummy even though of exact size cannot pass through the coin-race, because of the influence

of the magnet 25, which draws the same to one side and causes a lateral discharge thereof. A coin of given value after being passed through the slot 11 glides along the coin-race and is received in the coinway 8 and passes along the 70 same until it reaches the opening or pocket in the vending-slide, which latter when actuated in the usual manner effects delivery of the goods to be obtained.

A weight 26 rests upon the packages or 75 goods in the magazine 2 and has a pendent projection 27, which when the magazine is empty enters an opening 28 of the vending-slide and holds it open, thereby preventing 80 operation of the machine, and at the same time holding the coinway open, so that a coin dropped into the machine will return to the customer.

Having thus described the invention, what is claimed as new is—

85

1. In a vending-machine, a transversely-inclined coin-chute provided with a transversely-widened bottom opening and with an entrance-opening designed to direct the coin or the like face downward into the chute, so 90 that its rim will ride along one of the side edges bounding the bottom opening and said chute being also provided at the lower end of the lowermost side wall with a cut-away portion providing a lateral discharge, and the 95 chute being also provided on the opposite side with an extension in contiguous relation to the lateral discharge, as and for the purpose set forth.

2. In a vending-machine, the combination 100 with an article-ejecting device and means for actuating the same, of a coin-chute provided with an open bottom, a stationary wall bounding one side of said opening, a pivoted wall movable laterally on the bottom at the 105 other side of the opening therethrough and provided with a base-supporting ledge extending normally parallel to the opposite side edge of the bottom opening, the pivoted wall being provided at its free end with a depending arm 110 designed to abut against the outer side of the bottom to limit the inward movement of said wall, and the chute being arranged in an oblique plane and designed to receive a coin on its side whereby it will slide down the chute 115 while it is supported at diametrically opposite points on its face by the bottom at one side and the base-ledge on the pivoted wall at the opposite side, and a projection carried by the ejecting device and arranged in the 120 path of the arm whereby the actuation of the ejecting device will swing the said pivoted side.

3. In a vending-machine, the combination 125 with an article-ejecting device and means for actuating the same, of a coin-chute provided with an open bottom, a stationary wall bounding one side of said opening, a pivoted wall movable laterally on the bottom at the other side of the opening therethrough and 130

provided with a base-supporting ledge extending normally parallel to the opposite side edge of the bottom opening, the pivoted wall being provided at its free end with a depending arm designed to abut against the outer side of the bottom to limit the inward movement of said wall, and the chute being arranged in an oblique plane and designed to receive a coin on its side whereby it will slide down the chute while it is supported at diametrically opposite points on its face by the bottom at one side and the base-ledge on the pivoted wall at the opposite side, a spring secured at its upper end to the bottom of the chute and at one side edge thereof, with its free end engaging the outer side of said pivoted wall, and a projection carried by the ejecting device and arranged in the path of the arm whereby the actuation of the ejecting device will swing the said pivoted side.

4. In a vending-machine, the combination with an article-ejecting device and means for

actuating the same, of a transversely-inclined coin - chute provided with a transversely-widened bottom opening and with an entrance-opening designed to direct the coin or the like face downward into the chute so that its rim will ride along one of the side edges bounding the bottom opening, and said chute being also provided opposite said side edge with a pivoted wall having a bottom or base flange designed to coact with said edge to support the coin, a depending arm secured to the free end of said pivoted wall and a projection carried by the ejecting device and arranged in the path of the arm whereby the actuation of the ejecting device will swing the said pivoted side.

In testimony whereof I affix my signature in presence of two witnesses.
